Patented October 11, 1904.

UNITED STATES PATENT OFFICE.

HENRIK HILLBOM, OF WALLINGFORD, CONNECTICUT, ASSIGNOR TO R. WALLACE & SONS MFG. CO., OF WALLINGFORD, CONNECTICUT, A CORPORATION.

DESIGN FOR A BACK FOR MIRRORS, BRUSHES, OR SIMILAR ARTICLES.

SPECIFICATION forming part of Design No. 37,163, dated October 11, 1904.

Application filed September 9, 1904. Serial No. 223,923. Term of patent 7 years.

To all whom it may concern:

Be it known that I, HENRIK HILLBOM, a citizen of the United States, residing at Wallingford, in the county of New Haven and State of Connecticut, have invented a new, original, and ornamental Design for a Back for Mirrors, Brushes, or Similar Articles; and I do hereby declare the accompanying drawing to be a full, clear, and exact illustration of the same, and which said drawing constitutes part of this specification, and represents a face view of a back for a mirror, brush, or similar article.

I claim—

The ornamental design for a back for a mirror, brush, or similar article, as shown. 15

HENRIK HILLBOM.
